UNITED STATES PATENT OFFICE.

EMILE JEAN JULES SALMSON, OF BILLANCOURT, FRANCE, ASSIGNOR TO SOCIETE DES
MOTEURS SALMSON (SYSTEME CANTON-UNNE), OF BILLANCOURT, FRANCE.

ONE-PIECE FRAMING FOR MAGNETOS.

1,281,666.

Specification of Letters Patent.

Patented Oct. 15, 1918.

Application filed March 27, 1916. Serial No. 87,143.

To all whom it may concern:

Be it known that I, EMILE JEAN JULES SALMSON, citizen of the Republic of France, residing at 9 Avenue des Moulineaux, Billancourt, Seine, in the Republic of France, have invented new and useful Improvements in One-Piece Framing for Magnetos, of which the following is a specification.

This invention has for its object to provide an improved one-piece framing for magnetos which shall be equally applicable to ignition magnetos for internal combustion engines and to magnetos for lighting vehicles, whether they are of the revolving armature or the revolving shutter type.

The framings of magnetos as constructed hitherto, have been built up of a number of parts, so that perfect rigidity could never be assured, since such apparatus are subjected to the vibration due to the motion of the vehicle or engine to which they are fitted.

Now the improvement constituting the present invention facilitates considerably the manufacture and assumes a proper working of the magnetos; their getting out of order being rendered impossible because all the essential parts are mounted permanently on a rigid framing. Moreover, the framing is quite tight.

The invention will now be more particularly described with reference to the accompanying drawings which illustrate a constructional example thereof.

35 In these drawings:

Figure 1 is a longitudinal section of the framing taken in the plane of vertical symmetry.

Fig. 2 is a longitudinal section similar to Fig. 1 but showing the essential parts of the magneto (which in the example is of the rotating shutter type) for the purpose of facilitating the arrangement of the parts.

Fig. 3 is a cross section on the line A—A 45 of Fig. 2.

Fig. 4 is a cross section of the front portion of the framing on the line B—B of Fig. 2, showing particularly the construction of the interrupter of the magneto.

50 As shown, the framing which is made in one piece of gun-metal or aluminium, comprises essentially a base 1 by means of which the apparatus rests on the vehicle chassis or engine to which it belongs. Above the base and in front of same, (left side of Fig.

1) there is provided a part 2 approximately shaped as a body of revolution about the axis X, X¹, so as to constitute a bearing for supporting the main shaft of the magneto. Above the axis X, X¹, there is a second axis 60 Y, Y¹, parallel to the first axis, and situated like the latter in the plane of symmetry of the entire structure.

Two casings 3 and 4, situated one in front and the other behind the framing, designed for inclosing respectively the gears and the distributor, form bearings shaped as bodies of revolution about the axis Y, Y¹, for supporting the secondary shaft operating the distributor. The casings 3 and 4 65 are connected to each other and to the base by means of a middle part 5 of inverted U-shape which will be surmounted afterward by the magnets.

In the lower portion of the U are formed 75 two rectangular apertures situated one on each side of the plane of symmetry, for receiving the pole pieces. The two identically similar pole pieces 6, 6 are fitted in the apertures and held in place by end screws 7. 80 After the pole pieces have been placed in position, the metal of the framing is slightly upset all around the periphery of the pole pieces, whereby a perfectly tight joint is produced in a simple and effective manner, 85 constituting a metal-cased or armored construction which is so desired by engineers.

The magnets 8 straddling the U-shaped part are fixed to the pole pieces by means of screws 9. The lubricating holes 10 pierced 90 in the upper portions of the casings 3 and 4 in bosses provided for that purpose, enable the parts to be lubricated while in motion. An aperture 11 is formed in the forward and lower portion of the framing, on one 95 side only of the latter; it is intended to serve as a passage for the interrupter finger.

After the erection, covers are fitted in front on the part 2 and the casing 4, and at the back so as to make the apparatus quite 100 tight.

Figs. 2, 3 and 4 show more particularly the various parts of the magneto which are:—at the lower portion of the framing, the driving shaft d carrying the armature e, 105 the rotating shutter f, the interrupter cams g, the primary contact h connected to the low tension terminal i and the secondary contact k connected to the high tension terminal l. In the lower portion there is also 110

situated the interrupter *m* situated at the side. In the upper portion are the secondary shaft *n* carrying the rotary carbon brush holder *o* of the distributor, and the distributor body *p* with its several terminals. *q* is the condenser between the two shafts.

Having now described my invention, what I claim as new and desire to secure by Letters Patent is:

- 10 1. A one-piece framing for magnetos comprising essentially a base 1, a part 2 approximately shaped as a body of revolution about the axis of the armature, two casings 3, 4 situated one in front and the other behind the framing, designed for inclosing respectively the gears and the distributor, said casings forming bearings for supporting the secondary shaft operating the distributor and being connected to each other and to the base by means of a middle part 5 of inverted U-shape, two rectangular openings formed respectively at each side and at 35 the lower portion of the U-shaped middle part, designed for receiving the pole pieces, an aperture 11 formed in the forward and lower portion of the framing on one side of the latter, and lubricating holes 10 pierced 40 in the upper portions of the casings 3, 4 in bosses provided for that purpose, substantially as described and for the purpose set forth.
- 20 2. A one-piece framing for magnetos comprising essentially a base 1, a part 2 approximately shaped as a body of revolution about the axis of the armature, two casings

3, 4 situated one in front and the other behind the framing, designed for inclosing respectively the gears and the distributor, said casings forming bearings for supporting the secondary shaft operating the distributor and being connected to each other and to the base by means of a middle part 5 of inverted U-shape, two rectangular openings formed respectively at each side and at 35 the lower portion of the U-shaped middle part, designed for receiving the pole pieces, an aperture 11 formed in the forward and lower portion of the framing on one side of the latter, and lubricating holes 10 pierced 40 in the upper portions of the casings 3, 4 in bosses provided for that purpose, substantially as described and for the purpose set forth.

In testimony whereof I have signed my name to this specification in the presence of two subscribing witnesses.

EMILE JEAN JULES SALMSON.
